UNITED STATES PATENT OFFICE.

AUGUST HEINE AND GEORGE S. MACK, OF SILVER CREEK, NEW YORK;
SAID MACK ASSIGNOR TO SAID HEINE.

CONFECTIONER'S FILLING AND SEPARATING MACHINE.

SPECIFICATION forming part of Letters Patent No. 593,325, dated November 9, 1897.

Application filed April 13, 1897. Serial No. 631,941. (No model.)

To all whom it may concern:

Be it known that we, AUGUST HEINE and GEORGE S. MACK, citizens of the United States, residing at Silver Creek, in the county of 5 Chautauqua and State of New York, have invented a new and useful Improvement in Confectioners' Filling and Separating Machines, of which the following is a specification.

This invention relates to a machine for filling trays with a bed of powdered starch preparatory to forming the molding-cavities in the same in which the candies are cast and for cleaning and separating the candies from the starch after the confectionery has been 15 poured in the molds and become hard.

The object of our invention is to produce a simple, compact, and efficient machine whereby these operations are performed expeditiously and thoroughly and which can be 20 easily cleaned and repaired.

In the accompanying drawings, consisting of four sheets, Figure 1 is a longitudinal sectional elevation of our improved machine in line 1 1, Fig. 7. Fig. 2 is a fragmentary rear 25 elevation of the same. Fig. 3 is a longitudinal sectional elevation in line 3 3, Fig. 7. Fig. 4 is a fragmentary vertical transverse section in line 4 4, Fig. 1. Fig. 5 is a fragmentary front elevation of the separating 30 portion of the machine with the feed-hopper removed. Fig. 6 is a vertical transverse section in line 6 6, Fig. 3. Fig. 7 is a horizontal section in line 7 7, Fig. 10. Fig. 8 is a cross-section of the rear portion of one of the 35 separating-reels on an enlarged scale. Fig. 9 is a perspective view of one of the cleaner-linings of the rear portions of the separating-reels. Fig. 10 is a vertical cross-section of the machine in line 10 10, Fig. 7.

40 Like letters of reference refer to like parts in the several figures.

The main frame of the machine is preferably composed of two separable sections A A', arranged side by side for convenience in 45 shipping.

The mechanism for filling the molding-trays with powdered starch is mounted on the right-hand frame-section A, as shown in Figs. 3, 7, and 10, and is constructed as follows:

50 B represents a starch bin or receptacle into

which, previous to starting the machine, a quantity of loose or powdered molding-starch is introduced through an opening in the top thereof, which opening is closed by a lid b.

C represents a conveyer case or housing 55 which is arranged below the starch-bin and which communicates at its front and rear ends with the lower portion of the bin by transverse openings c c', formed in the front and rear sides of the bin, above the bottom 60 b' thereof. The bottom of the conveyer-casing is provided near its middle with a depending feed-spout c².

D represents a conveyer whereby the starch is removed from the bin and discharged into 65 the feed-spout. This conveyer consists of a number of transverse bars or drags d, secured to two endless chain belts d' d', which move in the direction of the arrow, Fig. 3, so that the bars enter through the rear opening of the 70 bin c', move over the bottom thereof, and remove the starch through the front opening c to the bottom of the conveyer-casing and thence to the feed-spout. The chains run around the sprocket-wheels d² d³, arranged, 75 respectively, in the front and rear portions of the conveyer-casing and secured to transverse shafts d⁴ d⁴, which are journaled in bearings in the side walls of the casing and which may be driven in any suitable manner. 80

E represents a rotating disintegrator which is arranged in the feed-spout c², and the starch is broken up and reduced to powder as it drops through the spout. This disintegrator consists, preferably, of two vertical disks e 85 and an annular row of horizontal beater-rods e', arranged between the disks. The latter are secured to a transverse shaft e², which is journaled in the side walls of the spout and which may be rotated in any suitable 90 manner.

F represents one of the trays or boxes which is carried past the lower end of the feed-spout and is filled with molding-starch through this spout. The trays are supported on two longitudinal rails or supports f f, arranged lengthwise under the feed-spout and secured to the bottom f' and the end boards f² of a box f³, which is secured, with its side boards f⁴, to the frame-section A. 95

G G represent two upright feed - rollers which engage against opposite sides of each tray and which feed the same from the front or receiving end of the rails rearwardly and 5 underneath the feed-spout. These rollers are arranged in front of the feed-spout and project slightly into the path of the trays. The rollers are made of rubber or other yielding material or are faced therewith, so that 10 when the tray is fed between the rollers the same are slightly compressed, thereby increasing the grip of the rollers on the tray and also permitting of slight variations in the width of the trays. These rollers are mounted 15 on the upper ends of two vertical shafts g g, which are journaled in bearings on the box f³, and which are driven by a horizontal shaft g', journaled transversely on the lower side of the box and provided with bevel gear-wheels g², which mesh with similar gear-wheels g³ on the lower ends of the roller-shafts, as 20 represented in Fig. 6. The location of the feed-rollers with reference to the feed-spout is such that when the rear end of the tray 25 has cleared the feed-rollers the tray stands underneath the feed-spout, where it remains until the next tray is fed forward by the feed-rollers, when such succeeding tray pushes the preceding tray forward and takes its place 30 underneath the feed-spout. These feed-rollers avoid the use of a chain conveyer or similar feed mechanism underneath the feed-spout, where rust on the chain tends to discolor the starch which comes in contact with 35 the same and necessitates a more frequent renewal of the starch.

g⁴ are guides which are secured to the sides of the box on opposite sides of the path of the trays and which serve to guide the trays 40 while being filled.

H represents a striker whereby the surplus starch is removed from the filled tray and the starch is leveled with the top of the tray. This striker is arranged horizontally 45 in rear of the feed-spout and has the form of a triangle, one corner of which is arranged in front and in line with the center of the path of the trays. The striker is capable of rising and falling to adapt itself to the top of the 50 tray and is guided by means of legs h h, arranged on the rear corners of the striker and moving in vertical guides h' h', arranged on the side boards of the box f³. The front end of the striker is held against downward displacement by a retaining cord or band h², which is secured with its upper end to the under side of the conveyer-casing and with 55 its lower end to a forwardly-projecting nose h³ on the front end of the striker. This nose 60 is curved on its under side, as shown at h⁴, Fig. 3. When there is no tray under the striker, the latter rests on the guide-bars g⁴. As the tray moves rearwardly underneath the striker the latter is lifted on top of 65 the tray by the front end of the tray engaging with the inclined nose of the striker.

During the continued rearward movement of the tray the inclined sides of the striker remove the surplus starch flush with the top of the tray. 70

I represents a hopper which is arranged in the bottom of the box f³ below the feed-spout and the striker and which catches the removed surplus starch and conducts the same into a transverse conveyer-trough i in the 75 bottom of the hopper. i' is a conveyer which is arranged in this trough and carries the starch to the foot of an elevator i², which latter discharges the starch at its upper end into the starch-bin. 80

After the trays have been filled with starch the surface of the latter is molded or impressed by a pattern which forms cavities in the starch of the desired shape of the confection. These cavities or molds are then filled with the confection. After the latter has become hard in the molds the finished candy is separated from the starch and cleaned by the following mechanism: 85

J J represent two cylindrical separating and cleaning reels which receive the contents of the trays, composed of candy and starch, and which separate the whole candy from the starch and the small fragments of candy. These reels are arranged lengthwise side by 90 side in the frame-section A' and incline from their front or receiving ends toward their rear or discharge ends. The front and rear ends of each reel are secured to cylindrical supporting rings or heads j j', which turn in circular openings k k', formed, respectively, in front and rear supporting-plates k² k³. The latter are secured in an inclined position to the front and rear portions of the frame-sections A' and form the front and rear walls of 100 the separating-chamber K, which incloses the reels. The front supporting-ring of each reel is provided with an annular flange k⁴, which bears against the front side of the front supporting-plate and holds the reel against backward movement. The reels are supported intermediate of their ends by means of two sets of rollers, which engage, respectively, with the front and rear supporting-rings of the 110 reels. Each set of rollers consists of a central roller l, which bears against the inner sides of the adjacent rings of both reels, and two outer rollers l' l', which bear against the outer sides of the same reel-heads. The inner rollers of both sets are mounted on a central longitudinal shaft l² and the outer rollers of each reel are mounted on an outer longitudinal shaft l³, the several roller-shafts being journaled at their ends in the front and rear supporting-plates. 115

L represents a driving-shaft journaled transversely in bearings on the front portion of the frame-section A' below the reels and provided with bevel gear-wheels l⁴, which mesh with similar gear-wheels l⁵, secured to 120 the front ends of the outer roller-shafts l³. 130

l⁶ l⁶ are gear-wheels which are arranged on

the outer roller-shafts in rear of the bevel gear-wheels l^5 , and preferably formed integrally with the latter, and which mesh with toothed gear-rims l^7 , formed on the flanges of the front supporting-rings, whereby motion is transmitted from the driving-shaft to the reels for turning the latter.

M represents a feed-hopper into which the candy and starch are discharged from the trays by the operator and whereby the same are delivered into the front ends of the separating-reels. This hopper is arranged transversely in front of the front supporting-plate and consists of transverse front and rear boards or plates $m^1 m^1$, which converge downwardly in the form of the letter V, and two end boards or plates m^2 . The rear board m^1 of the feed-hopper is arranged close to the front supporting-rings and is provided with two circular openings $m^3 m^3$, which register with said rings.

$m^4 m^4$ represent annular flanges or rims which are arranged on the rear side of the rear hopper-plate and which fit against the inner side of the front supporting-rings, so as to cover the joints between the feed-hopper and said rings. The feed-hopper is detachably secured in place in any suitable manner—for instance, by means of bolts m^5 , which connect the rear plate of the hopper with the front supporting-plate.

m^6 is an upwardly-projecting hood or guard which is secured to the frame-section A' along the rear and sides of the feed-hopper and which reduces the spreading of the starch-dust when the contents of the molding-trays are dumped into the hopper. After the operator has emptied a tray into the feed-hopper he places the same between the feed-rollers of the filling mechanism, whereby the tray is again carried under the feed-spout and filled preparatory to being impressed with the candy-pattern.

The greater portion of each reel from its front end toward its tail is provided with a clothing of wire-cloth. As the wheels revolve the starch and candy delivered into the same are separated, the starch and small broken particles of candy passing through the meshes of cloth, while the whole candy tails off upon an inclined chute m^7 , which is secured to the rear supporting-plate. The bulk of the starch is separated from the whole candy by the swinging action of the front portions of the reels. In order to remove the starch which still adheres to the candy, the latter is subjected to brushing operations before it is discharged from the reels. The mechanism for effecting these operations is constructed as follows:

Each of the reels contains a rotary brush consisting of a front section N and a rear section N', the front section being arranged in the central portion of the reel and the rear section in the rear portion of the reel. The brush-sections are mounted on a longitudinal

shaft n , which is arranged axially in the reel and which extends with its front end only to about the front end of the front supporting-ring, while its rear end extends beyond the rear end of the rear supporting-ring.

$n' n'$ are curved hangers which are adjustably secured to the rear hopper-plate above the outlet-openings therein by means of bolts n^2 , passing through vertical slots n^3 in the hangers and which are provided at their lower ends with bearings n^4 , in which the front ends of the brush-shafts are journaled. The lower portions of the hangers extend rearwardly into the front supporting-rings of the reels, so as to leave the space in the lower portion of the feed-hopper clear and unobstructed, thereby avoiding choking of the outlets thereof.

o represents a carrier-plate provided at its lower ends with bearings o^1 , in which the rear ends of the brush-shafts are journaled. This plate is adjustably secured with its upper portion to the rear side of the rear supporting-plate by bolts o^2 , passing through vertical slots o^3 in the carrier-plate. The carrier-plate may be raised and lowered by means of adjusting-screws o^4 , journaled with their upper ends in lugs o^5 on the rear supporting-plate and engaging with their lower screw-threaded ends in internally-screw-threaded lugs o^6 on the carrier-plate.

o^7 is a horizontal driving-shaft journaled transversely in bearings o^8 on the carrier-plate and provided with bevel gear-wheels o^9 , which mesh with similar gear-wheels o^{10} on the rear ends of the brush-shafts, whereby motion is transmitted from the driving-shaft to the brushes. The front section of each brush bears directly against the screen-surface of the reel and rubs the candies against the same, whereby the starch is partly removed from one side of the candy by rubbing against the screen, while the starch is removed from the opposite side by the brush.

The greater portion of all candy which is cast in starch-molds has a substantially conical form. It has been found in practice that when candy of this form is operated upon in a rotary screen the candies usually slide with their base or flat side around the inner side of the screen, so that the base of the candy is not presented to the action of the brushes, which results in an imperfect removal of the starch from the base. For the purpose of overcoming this difficulty a portion of each reel is provided with a wiper or cleaner P, of plush, velvet, or similar material, having a more or less rough pile, nap, or fiber, whereby the base of the candy while sliding over the same is wiped and cleaned. This lining is preferably arranged in the rear portion of the reel, as shown, so that the candy before issuing from the reel will be wiped simultaneously on its flat side by the wiper and on its conical side by the rear section of the rotary brush. By arranging the wiper in the deliv-

ery portion of the reel the candy does not come in contact with the same until nearly all the starch has been removed therefrom, and the wiper is only required to remove the fine particles of starch which still adhere to the base of the candy, thereby reducing the clogging or filling of the wiper to a minimum.

In order to afford a ready escape for the starch which is removed from the candy by the rear brush-section and the wiper, the latter is provided with a longitudinal slot or gap p , through which the detached starch escapes. This slot is covered by the reel-clothing, so as to prevent the escape of the candy through the same. The wiper is preferably supported by a backing p' , of sheet metal, to which it is secured by gluing or otherwise. This backing may be fastened to the inner side of the reel-clothing by bolts p^2 , Figs. 8 and 9, or the reticulated or perforate clothing can stop at this imperforate backing except where it is required to cover the slot in the same. The diameter of the reels and of the front and rear supporting-rings is no larger than the circular openings in the front supporting-plate, so that the screens and connecting parts can be withdrawn forwardly through these openings for cleaning or repairing after removing the feed-hopper M and the shaft-hangers n' .

Q represents a flat screen which is arranged lengthwise underneath the reels and which receives and separates the starch and small pieces of candy which drop from the reels. This screen inclines rearwardly and projects with its tail end through a transverse opening q in the rear supporting-plate. A vertically shaking or tossing movement is imparted to this screen by cams q' , which are secured to the outer roller-shafts and which engage in overhanging yokes q^2 , connected with the lower screen and resting on the cams. The fragments of candy tail off from the lower screen, while the starch passes through the same and drops upon the flat rear portion q^3 and the inclined front portion q^4 of the bottom of the separating-chamber.

R represents a transverse conveyer-trough which is arranged between the front and rear bottom portions $q^3 q^4$ and which connects with the conveyer-trough i below the tray-filling mechanism. The conveyer-trough R contains a conveyer which is an extension of the same transverse conveyer i' which works in the trough i .

r is a longitudinal conveyer whereby the starch is removed from the rear flat portion of the bottom into the conveyer-trough R , and which consists of two endless chain belts $r' r'$, which are connected by transverse conveyer bars or drags r^2 and which pass around sprocket-wheels $r^3 r^4$. The latter are mounted on shafts $r^5 r^6$, which are journaled in bearings in the side walls of the separating-chamber. Upon moving the chain belts in the direction of the arrow, Fig. 1, the drags carry the starch from the rear portion of the bot-

tom of the chamber into the conveyer-trough, from which latter the starch is carried by the conveyer i' into the foot of the elevator, together with the starch which spills over during the operation of filling the trays, and is again elevated into the bin to be used over again.

For the purpose of gathering the starch-dust in the different parts of the machine and preventing its escape from the machine a dust-collector is provided, which is constructed as follows:

S represents a suction-chamber arranged on top of the separating-chamber, and T is a fan having its eye opening into the suction-chamber, while its blast-spout extends outside of the suction-chamber.

t represents a number of vertical filtering-tubes of woven cotton or similar material, which have their upper ends closed and which are secured with their open lower ends around openings t' , formed in the bottom of the suction-chamber, whereby the tubes are placed in communication with the separating-chamber. The suction of the fan draws the dust-laden air from the separating-chamber, the feed-hopper, and the space below the tray-filling mechanism into the filtering-tubes, the starch being separated from the air by the tubes and clinging to the inner side thereof, while the purified air passes through the tubes to the fan. The closed upper ends of the filtering-tubes are secured to a vertically-movable head u , which in its highest position draws the tubes taut and bears against the under sides of two cross-bars u' , which are secured to the side walls of the suction-chamber. The movable tube-head is yieldingly held in an elevated position by springs u^2 , bearing with their lower ends against the top of the cross-bars and with their upper ends against shoulders on rods u^3 , which are connected with the tube-head.

v represents rotary tappets or cams which are adapted to engage with lugs or projections v' on the upper side of the tube-head for depressing the latter and producing a slack in the filtering-tubes. These cams are secured to transverse shafts v^2 and are rotated in unison by a chain belt v^3 , passing around sprocket-wheels v^4 , secured to the cam-shafts. When the cams are disengaged from the lugs on the tube-head, the latter is raised suddenly by the springs u^2 , whereby the tubes are shaken and the dust is detached and falls into the separating-chamber.

We claim as our invention—

1. The combination with a bin provided with openings on opposite sides above its bottom, of a conveyer-casing arranged below said bottom and communicating with said openings and provided with an outlet, and an endless conveyer passing through said openings of the bin and over the bottoms of the bin and conveyer-casing, substantially as set forth.

2. The combination with the starch-bin, of

a conveyer whereby the starch is removed from the bottom of said bin, a feed-spout to which the starch is delivered by said conveyer, and a disintegrator arranged in said feed-spout, substantially as set forth.

5 3. The combination with the starch-bin, of a conveyer whereby the starch is removed from the bottom of said bin, a feed-spout arranged below said conveyer and to which the starch is delivered by said conveyer and a tray-feeder arranged below said feed-spout, substantially as set forth.

10 4. The combination with the starch-bin, of a conveyer whereby the starch is removed from the bottom of said bin, a feed-spout to which the starch is delivered by said conveyer, a disintegrator arranged in said feed-spout, and a tray-feeder arranged below said feed-spout, substantially as set forth.

15 5. The combination with the starch-bin, of a conveyer whereby the starch is removed from the bottom of said bin, a feed-spout to which the starch is delivered by said conveyer, and a disintegrator arranged in said feed-spout and consisting of a horizontal shaft, disks secured thereto and rods connecting said disks, substantially as set forth.

20 6. The combination with the feed-spout and the tray-guides arranged below the same, of feed-rollers adapted to engage against opposite sides of the trays and operating to move the same underneath the feed-spout, substantially as set forth.

25 7. The combination with the feed-spout and the tray-guides arranged below the same, of elastic feed-rollers adapted to engage against opposite sides of the trays and operating to move the same underneath the feed-spout, substantially as set forth.

30 8. The combination with the feed-spout and the tray-guides arranged below the same, of a triangular striker arranged in rear of the feed-spout, and capable of vertical yielding movement, vertical guides in which the rear portion of the striker is guided, and a retaining-band whereby the front portion of the striker is held against downward displacement, substantially as set forth.

35 9. The combination with the separating-chamber provided in its front and rear ends with circular openings, of a rotary screen provided at its receiving and delivery ends with supporting-rings which turn in said openings, substantially as set forth.

40 10. The combination with the separating-chamber, and the front and rear supporting-plates provided with circular openings, of a rotary screen provided at its receiving and delivery ends with supporting-rings which turn respectively in the openings of the front and rear plates, and an annular flange arranged on the front supporting-ring and bearing against the front side of the front supporting-plate, substantially as set forth.

45 65 11. The combination with the separating-chamber, and the front and rear supporting-

plates provided with circular openings, of a rotary screen provided at its receiving and delivery ends with supporting-rings which turn respectively in the openings of the front and rear plates, and an annular flange arranged on the front supporting-ring and bearing against the front side of the front supporting-plate, the diameter of the screen and its supporting-rings being no larger than the diameter of the opening in the front supporting-plate so as to permit the screen and rings to be withdrawn through the front opening, substantially as set forth.

70 12. The combination with the separating-chamber, and the front and rear supporting-plates provided with circular openings, of a rotary screen provided at its receiving and delivery ends with supporting-rings which turn respectively in the openings of the front and rear plates, an annular flange formed on the front ring and provided with a gear-rim, a spur gear-wheel meshing with the gear-rim and provided with a bevel gear-wheel and a driving-shaft provided with a bevel-gear which meshes with the bevel gear-wheel on the spur gear-wheel, substantially as set forth.

75 13. The combination with a rotary screen, of longitudinal shafts provided with rollers which support said screen, a vertically-shaking screen arranged below the rotary screen, and cams arranged on said shafts and actuating the vertically-shaking screen, substantially as set forth.

80 14. The combination with the separating-chamber provided with circular openings in its front and rear ends, of a rotary screen provided at its receiving and delivery ends with supporting-rings which turn in said openings, a feed-hopper provided with a discharge-opening which registers with the receiving end of the screen, and an annular flange secured to the hopper around the discharge-opening thereof and fitting against the inner side of the front supporting-ring, substantially as set forth.

85 15. The combination with the rotary screen and the feed-hopper which opens into the receiving end of the screen, of a rotary brush arranged in the screen and mounted on a shaft which does not project beyond the front end of said screen, and a hanger which is secured with its upper end to said hopper and provided at its lower end with a bearing in which the brush-shaft is journaled and which projects rearwardly into the screen, so as to clear the lower portion of the feed-hopper, substantially as set forth.

90 16. The combination with a screen, of an imperforate fibrous wiper moving with the screen and forming a continuation thereof, substantially as set forth.

100 17. The combination with a rotary screen, of an imperforate fibrous wiper rotating with the screen and provided with a slot or gap which is provided with a perforate covering, substantially as set forth.

18. The combination with a rotary screen, of an imperforate fibrous wiper rotating with the screen and provided with a slot or gap which is provided with a perforate covering, 5 a rotary brush engaging with the inner side of the screen and a rotary brush engaging with said wiper, substantially as set forth.

Witness our hands this 7th day of April, 1897.
